(57) **CLAIM**

The ornamental design for a video camera display panel or screen with an animated graphical user interface, as shown and described.

DESCRIPTION

FIG. 1 is a front view of a video camera display panel or screen showing a first image in a sequence according to a first embodiment of our new design; and
FIG. 2 is a front view thereof showing a second image in the sequence.

FIG. 3 is a front view of a video camera display panel or screen showing the first image of the first embodiment in a differing broken-line context; and

FIG. 4 is a front view thereof showing the second image in the sequence in a differing broken-line context.

FIG. 5 is a front view of a video camera display panel or screen showing the first image in a sequence according to a second embodiment of our new design; and

FIG. 6 is a front view thereof showing a second image in the sequence.

FIG. 7 is a front view of a video camera display panel or screen showing the first image of the second embodiment in a differing broken-line context; and

FIG. 8 is a front view thereof showing a second image in the sequence in a differing broken-line context.

FIG. 9 is a front view a video camera display panel or screen showing the first image in a sequence according to a third embodiment of our new design; and

FIG. 10 is a front view thereof showing a second image in the sequence.

FIG. 11 is a front view of a video camera display panel or screen showing the first image of the third embodiment in a differing broken-line context; and

FIG. 12 is a front view thereof showing a second image in the sequence in a differing broken-line context.

FIG. 13 is a front view of a video camera display panel or screen showing the first image in a sequence according to a fourth embodiment of our new design; and

FIG. 14 is a front view thereof showing a second image in the sequence.

(Continued)

FIG. 15 is a front view of a video camera display panel or screen showing the first image of the fourth embodiment in a differing broken-line context; and, FIG. 16 is a front view thereof showing a second image in the sequence in a differing broken-line context. With respect to the first embodiment, the appearance of a first transitional image sequentially transitions between the images shown in FIGS. 1 and 2 or between the images shown in FIGS. 3 and 4. With respect to the second embodiment, the appearance of a second transitional image sequentially transitions between the images shown in FIGS. 5 and 6 or between the images shown in FIGS. 7 and 8. With respect to the third embodiment, the appearance of a third transitional image sequentially transitions between the images shown in FIGS. 9 and 10 or between the images shown in FIGS. 11 and 12. With respect to the fourth embodiment, the appearance of a fourth transitional image sequentially transitions between the images shown in FIGS. 13 and 14 or between the images shown in FIGS. 15 and 16. The process or period in which one image transitions to another forms no part of the claimed design.

The broken lines in the drawings illustrate portions of a video camera display panel or screen with animated graphical user interface, or portions of an animated graphical user interface, and form no part of the claimed design. The round-cornered rectangular broken-line border shown just outside the outermost sharp-cornered solid-line rectangle illustrates the perimeter of the display panel or screen of a video camera and forms no part of the claimed design. The broken lines of the circles within the rounded-cornered rectangular border form no part of the claimed design.
